UNITED STATES PATENT OFFICE.

MORTON W. STERNS, OF JAMAICA, NEW YORK.

WIRELESS TELEPHONE SYSTEM.

Application filed January 24, 1925. Serial No. 4,397.

My invention relates to a radio or guided radio system or apparatus for simultaneous sending and receiving. The main object is to provide for apparatus which can be used in a manner substantially as simple as the ordinary wire telephone so that two parties can carry on a conversation together and without interruption such as is occasioned by the use of hand or automatic switches.

Another object is to provide simple and compact apparatus which can be used for either transmitting or receiving or both.

Another object is to provide for maximum power effect with a simple circuit and small expense of apparatus.

Another object is to utilize the same vacuum tube or tubes for transmission as well as reception.

In its preferred form the invention contemplates the use of a three-electrode tube or oscillation device with the anode or output circuit inductively connected with the aerial or loop. In my original application No. 354,611, filed January 28, 1920, Patent No. 1,524,413, January 27, 1925, I have claimed the invention broadly and also specifically claimed one form in which the anode is directly connected to the aerial. This application is a partial division from said former application. This case also involves improvements for high power work with a filter to cut out generator hum and an amplifier for weak signals.

Fig. 1 is a diagrammatic view of one arrangement of apparatus or circuit embodying the improvements of my invention.

Figs. 2, 3 and 4 are similar diagrammatic views showing other modifications of my invention.

Fig. 5 shows an improved high power circuit.

I have shown diagrammatically a typical telephone transmitter 5, receiving device 6, aerial or antenna loop 7, and an oscillation device 8.

In the preferred form the oscillation device is a vacuum tube having a filamentary cathode 9 with the usual battery and adjustable resistance, an anode or plate 10, and a control element or grid 11.

The primary coil 12 of the telephone receiver transformer and the source of power, in this instance a battery 13, are connected in series between the filament circuit and the plate.

The secondary coil of the telephone transmitter transformer is connected between the grid

and the filament. Obviously the transmitter and receiver may be located at some distance from the remainder of the set, if desired, and operation carried on by remote control.

The loop circuit includes the tuning capacity 15 and inductance 16, the latter being variably coupled with the coil 17, which is connected to the oscillation device. In this case one end of the coil 17 is connected by a lead 18 to the plate 10 and the other end of the coil is connected to the grid but with a condenser 19 interposed. The variable capacity 20 is connected between the grid and the plate through the condenser 19. A capacity 21 is also interposed between the grid and the filament through the condenser 19, and a capacity 22 between the filament and plate.

The resistance of the secondary 14 of the telephone transmitter should be kept low enough so as to maintain the grid 11 at the same potential as the negative end of the filament, that is, low enough to prevent the grid from collecting a positive charge. The impedance of the secondary of the modulation transformer or induction coil should equal the input impedance of the tube or tubes, or the impedance between the grid and the filament. Furthermore the impedance of the primary of the transformer should equal the impedance of the transmitter, buzzer or other alternating current source. The ratio of the primary to the secondary should be large so as to impress a high potential on the grid.

On the other hand, in the plate or power circuit the impedance of the primary should equal the impedance of the circuit into which it is inserted, and the impedance of the secondary should equal the impedance of the circuit into which it feeds, such as a receiver or amplifying device. A strong D. C. which supplies power to the plate circuit will not affect the receiving device, but any weak A. C. effect, such as received signals or your own voice in the transmitter, will affect the receiving device.

Referring to Fig. 1 as a typical embodiment of my invention the operation is as follows:

The battery 13 supplies energy to the anode 10 of the vacuum tube 8. On account of the feed back condensers 21 and 22 the tube 8 will generate oscillations in the closed oscillating circuit consisting of the inductance 17 and the variable condenser 20 and the frequency of these oscillations may be controlled by the adjustment of the condenser 20. The

inductance 17 may be coupled to a tuned loop as shown in Fig. 1 or to an inductance included in circuit with a tuned antenna system (as in Fig. 3). The telephone transmitter 5 acting through the modulation transformer 14 varies the potential, with respect to the filament, of the grid 11 and hence modulates the amplitude of said oscillations substantially in accord with the voice frequency applied to the transmitter 5, thus causing the system to act as a radio telephone transmitter.

On the other hand, an electromagnetic wave of resonant frequency impinging on the antenna system will vary the potential of the grid 11 and hence vary the current flowing through the primary of the telephone transformer 12 thus producing audible signals in the telephone receiver 6 whose magnitude will vary substantially as the magnitude of the impinging wave, thus causing the system to act as a radio telephone receiver.

In practice, two or more stations would be tuned to the same frequency, reception being accomplished by the homodyne or zero beat principle so that no heterodyne note would be produced. It is obvious then that if this system is used the party talking can not only hear his own voice, similar to the familiar "side talk" of the conventional wire telephone, but can be interrupted by the listener at any time in case of misunderstanding or inability to hear properly, thus constituting another feature common to wire telephony but not to single channel radio telephony heretofore.

With the foregoing apparatus it is possible to simultaneously transmit and receive on the same aerial and with the same wave length and the same tube without the use of any switches, the operators at the opposite ends of such a system talking and listening at the same time as on ordinary wire lines.

In case station A wishes to speak telephonically with station B, station A will say, "Hello B, Hello B, A calling, A calling, answer please." Station B on hearing A will tune to A's wave length automatically as that is the point of loudest and clearest speech reception. If B now speaks to A, A will hear him, as he is tuned to the same wave length as B, due to the previous operations. It is evident therefore that A can break in on B, or vice versa, at any instant and ask for a repeat in case of misunderstanding or for any other purpose and without throwing any switches. This circuit will therefore give all the advantages of an ordinary land line telephone with the added advantage of the peculiarly clear speech which is a well known advantage of the radio telephone.

The connections of the filament and plate to the aerial may be transposed, but in any case the positive of the source of power 13 should be connected to the plate. The plate and grid connections to the aerial may also be transposed. A receiving device may be

inserted in or coupled with the source of power. The plate may be directly connected to the aerial, as in the parent application. The grid may also be directly connected to the aerial but with a condenser interposed. In low power systems the telephone instruments may be inserted directly in the circuits, as shown in my earlier application.

In Fig. 2 I have shown an aerial 25 grounded at 26 and provided with a variable inductance 27 which is coupled with the grid and plate circuits by means of the coils 28 and 29. In this case it will be seen that the telephone receiver is also connected between the plate and the power source.

In the arrangement of Fig. 3 the transmitting and receiving circuits are inductively coupled with the aerial by means of the coil 30 which is connected on opposite sides of the condensers 31 and 32, the latter being interposed between the grid and filament, and the plate and filament, respectively.

In the arrangement shown in Fig. 4 the aerial has a variable inductance 33 and capacity 34, and the grid and plate are inductively coupled through the coils 33 and 35. In this case the telephone receiver 6' is connected directly to the power circuit, but the transmitter is connected between the grid and filament, as in the previously described arrangement. It is obvious that the receiving device can also be inductively connected to the power source if desired.

In the arrangement shown in Fig. 5 there are two tubes 8 and 8' in parallel and a generator 13'. I have also shown a radio frequency by-pass 36, a filter 37, and an amplifier 38 connected to the receiving phone 39 presumably located at some distance away. I have also shown an amplifier 40 in the circuit leading to the transmitter microphone 41 or other long distance line (not shown). In this case the loop 7' replaces the coil 17 so that the loop is directly connected in the circuit.

Such an arrangement can be used for simultaneous broadcasting and reception.

From the above it can be seen that the transmitting and receiving device can be added to any oscillating circuit if proper precautions are taken to place them in their proper places as shown in the examples above.

It will be seen from the foregoing that according to my invention no separate receiving set is required. All the tubes serve as oscillators and yet produce results which in ordinary sets would require as many modulators as oscillators. For instance according to my invention we can use four oscillators in place of two oscillators and two modulators thus doubling the power of the set.

I claim:

1. In a single radio set for both transmission and reception, an antenna system, an

oscillation generator having a cathode, an anode, and a control element, said anode and said control element being connected by a circuit including a control element condenser 5 and a tuning inductance, said tuning inductance being magnetically coupled to said antenna system, said control element having a modulating device included in its associated circuits and said anode having a telephone 10 receiving device connected in its associated circuits.

2. In a single radio system for both transmission and reception, an antenna system which is used as both a radiator and an absorber without change of circuit connections, an oscillation generator having a cathode, an anode, and a control element, said anode and said cathode being connected by a circuit including a control element condenser 15 and a tuning inductance, said tuning inductance being magnetically coupled to said antenna system, said control element having a modulation device connected in its associated circuits and said anode having a telephone 20 receiving device connected in its associated circuits.

3. In a single radio system for both transmission and reception, an antenna system, a vacuum tube having an anode, a cathode, and 30 a control element, said anode being connected to said control element by a circuit including a control element condenser and a tuning inductance, said inductance being magnetically coupled to said antenna system, said vacuum 35 tube having associated circuits such that it may function as either a voice modulated oscillator or a homodyne detector.

4. In a single radio system for both trans-

mission and reception, a single antenna system which may be used for both radiation and 40 reception without alteration of any circuits comprising said system, an oscillation device having a cathode, an anode, and a control electrode, a circuit including a control element condenser and a tuning inductance connecting said anode and said control electrode, said inductance being coupled to said antenna system, a telephone transmitter connected to the primary of a modulation transformer 45 the secondary of said modulation transformer being connected between said cathode and said control element, and a telephone receiving device whose circuits are associated with said cathode.

5. In a single radio system for both transmission and reception, a single antenna system which may be used for both radiation and reception without alteration of any circuits comprising said system, an oscillation device having a cathode, an anode, and a control electrode, a circuit connecting said anode and said control electrode, said circuit including a control element electrode and a tuning inductance, said inductance being coupled to said antenna system, a telephone 65 transmitter connected to the primary of a modulation transformer, the secondary of said modulation transformer being connected between said cathode and said control element, and a telephone transformer whose primary is in series with a direct current 70 source and connected between said anode and said cathode, the secondary of said transformer being connected to a telephone receiver.

MORTON W. STERNS.
